UNITED STATES PATENT OFFICE.

BENJAMIN BERMAN, OF BOSTON, MASSACHUSETTS.

KEY HOLDER.

1,412,602.

Specification of Letters Patent. Patented Apr. 11, 1922.

Application filed May 27, 1921. Serial No. 473,021.

To all whom it may concern:

Be it known that I, BENJAMIN BERMAN, a citizen of the United States, residing in Boston, in the county of Suffolk and State of Massachusetts, have invented an Improvement in Key Holders, of which the following description, in connection with the accompanying drawings, is a specification, like characters on the drawings representing like

10 parts.

This invention relates to key holders of that character in which a plurality of keys are capable of being assembled within a folder and carried in compact form in the 15 pocket without liability of the keys making holes in said pocket.

The present invention has for its object to provide a simple, efficient and inexpensive device of the character described and one 20 which has provision for carrying an identification card, as will be described.

The particular features of the invention will be pointed out in the claims at the end of this specification.

25 Fig. 1 represents a key holder embodying this invention in its closed position, the key-holding frame with a key attached being shown in dotted lines.

Fig. 2, a view with the folder open and the 30 key holders in their operative position.

Fig. 3, a section on the line 3—3, Fig. 2.

Fig. 4, a like section on a larger scale, and Fig. 5, a detail to be referred to.

Referring to the drawings, *a* represents an 35 open sheet metal frame substantially rectangular in form and provided with top and bottom bars 10, 12, side bars 13, 14, and an intermediate cross bar 15, which latter divides the frame into upper and lower openings 16, 17. The frame *a* is further provided with corner lugs 18 extended into the 40 openings 16, 17, for a purpose as will be described.

The frame *a* is also provided with a plurality of supporting fingers 20, which are integral with the bottom bar 12 and are formed by bending normally flat fingers into substantially circular form, as represented in Figs. 3 and 4. The fingers 20 are spaced 45 apart and have hung thereon a plurality of devices 21 for holding the keys 22.

The key holding devices 21 are preferably made of wire and each is provided with a closed eye 23 and with a hook 24. The eyes

23 are hung upon the fingers 20 before the latter are closed, after which the latter are closed as represented in Figs. 3 and 4 to prevent accidental disengagement of the holding devices 21.

The fingers 20 are made of such size as to 60 permit the eyes 23 of the holding devices to turn freely therein both vertically and laterally.

The holding devices 21 are designed to receive the keys 22 only one of which is shown, 65 and said keys are readily detachable by hand.

The sheet metal frame *a* is secured to a folder 25 of leather or other flexible suitable material by rivets or like devices 26 passed 70 through the corners of said frame, and the latter is located on the folder with its fingers 20 close to the lower edge of the holder but sufficiently removed therefrom to be covered by the flaps 28, 29, of the folder when the 75 keys and their holding devices are folded up and over upon the folder as represented in Fig. 1. The open frame *a* is designed to hold an identification card 30, such as the card of the owner of the keys, whereby in 80 case of loss the keys may be recovered.

The identification card 30 is herein represented as a blank card, which is laid over the cross bar 15 of the frame *a* and has its upper and lower edge portions extended 85 under the corner lugs 18 of said frame (see Fig. 5), from which the card can be readily removed when it is desired to renew the same. The flaps 28, 29, of the folder are provided with the members 31, 32, of a snap 90 fastener of known construction and such as now commonly used on gloves, and by means of which the flaps may be secured in their closed position shown in Fig. 1 with the keys and their holding devices 21 assembled in 95 compact form and covered by the folder so as to protect the pocket from being punctured by the keys. The folder may be carried loosely in the pocket or it may be provided with an eyelet 35 for attachment to 100 the usual key chain, not shown, but such as now commonly used for securing a bunch of keys to the trousers.

When it is desired to gain access to any particular key, the flaps 28, 29, are opened 105 up into the position shown in Fig. 2 and the folder is held so as to allow the keys to drop by gravity into the position shown in Fig. 2.

When it is desired to restore the keys to the pocket, the keys and their holding devices 21 are turned over upon the folder and into the position represented in Fig. 1, and 5 the flaps are then closed and fastened together.

The open frame *a* and the fingers which form the fingers 20 are stamped out of sheet metal, and the fingers are then bent or 10 curved to partially close them, and after the eyes 23 of the holding devices 21 have been engaged with the fingers, the latter are closed, and the frame is riveted or otherwise secured to the folder, with the result that a 15 simple, efficient and inexpensive key-holder is obtained, which has provision for holding a card for identifying the owner of the keys.

Claims.

1. In a key holder of the character described, in combination, a folder provided with side flaps, an open metal frame attached to said folder and provided with inwardly extended corner lugs and with an intermediate cross bar co-operating with 20 said corner lugs to secure an identification card to said frame, supporting fingers integral with said frame and spaced apart, key holding devices engaged with said support- 25

ing fingers, and means for securing said open frame to said folder.

2. In a key holder of the character described, in combination, a folder provided with side flaps, an open metal frame attached to said folder and provided with means for detachably securing an identification card to said frame, supporting fingers integral with said frame and spaced apart, key holding devices engaged with said fingers, and means for securing said open frame to said folder.

3. In a key holder of the character described, in combination, a folder provided with side flaps, an open metal frame attached to said folder and provided with side bars, top, bottom and an intermediate bar 45 connecting said side bars, corner lugs extended into the opening in said frame to engage an identification card passed over said intermediate bar, and supporting fingers integral with said bottom cross bar and 50 spaced apart, and key-holding devices engaged with said fingers.

In testimony whereof, I have signed my name to this specification.

BENJAMIN BERMAN.
